ATTORNEY.

UNITED STATES PATENT OFFICE.

CHARLES R. LAUGEL, OF BERKELEY, CALIFORNIA.

APPARATUS FOR DECORATING MIRRORS.

Application filed June 22, 1927. Serial No. 200,729.

My invention relates to apparatus for removing a predetermined area of the coating from a mirror for decorative purposes.

An object of the invention is to provide 5 apparatus of the class described which is arranged to produce a particularly clear and distinct line of demarcation at the edges of the unremoved coating portions defining an area from which the coating has been 10 removed.

Another object of the invention is to provide apparatus of the class described which may be used repeatedly.

A further object of the invention is to 15 provide apparatus of the character described such that only the outline of an area of the coating to be removed is arranged to be defined thereby.

The invention possesses other objects and 20 features of advantage, some of which, with the foregoing, will be set forth in the following description of the preferred form of the invention which is illustrated in the drawings accompanying and forming part of the 25 specification. It is to be understood, however, that I do not limit myself to the showing made by the said drawings and description as I may adopt variations of the preferred form within the scope of my 30 invention as set forth in the claims.

Referring to said drawings:

Figure 1 is a perspective view showing a template forming part of the apparatus of my invention operatively mounted on and 35 against the silvered side of a mirror to be decorated.

Fig. 2 is a sectional view taken on the line 2—2 in Figure 1, the thickness of the various layers being exaggerated.

Fig. 3 is a sectional view of the mirror 40 taken on the line 2—2 after the picture has been mounted on the mirror.

Fig. 4 is a view similar to Figure 2 showing a modified use of the apparatus.

In decorating mirrors on their silvered 45 sides, experience has shown that covering over the back of the decorative matter with silvering is generally unsatisfactory, chiefly because the silvering tends to corrosively act 50 on the color pigments of the decorative matter and "creep" inwardly along its edges to spoil its appearance. It accordingly becomes necessary that the silvering do not overlap the decorative matter and that sharp 55 and distinct boundaries be provided about the edge of the decorative matter at its

juncture with the silvering. Furthermore, quantity production favors the use of pre-silvered stock glass, it being noted that the method of my invention is applicable to 60 different varieties of pre-silvered mirror glass without regard to the nature of the silvering thereon.

As herewith particularly shown my invention is utilized in effecting the placing on 65 the silvered side of a mirror 6 of a decorative figure, or picture, 7 of desired shape and color. The mirror 6, it will be noted, comprises a sheet of glass 8 having one side thereof covered with an adhering coat of 70 silvering 9 which is in turn covered with a filling and binding layer 11 of a suitable material such as shellac and an overlying protective coating 12 of an asphaltic varnish or the like. To provide for the placing of 75 the picture 7 on the mirror the method of my invention includes the removal of a suitably shaped portion of the silvering and other coatings, after which the figure 7 may be directly painted on the glass in the area 80 provided therefor or may, as is herewith particularly shown, be provided in the form of a picture previously formed on a surface of a suitable backing material 13 therefor which may be glued to the glass with its 85 picture-side thereagainst.

As hereinbefore pointed out the provision of a sharp outline at the juncture of the silvering and the decorative figure is particularly desirable, and it is to a means for 90 providing such an outline that my invention particularly relates. Accordingly, and as here shown, I utilize a template 14 formed of sheet metal or other shape-retaining material and having provided therein an opening 95 16 defining the outline of the figure 7. With the template removably fixed against the silvered side of the glass in desired position by means of suitable clamps 17 or the like, the stream from a sand blast 5, Fig. 4, is 100 directed within and against the template and exposed mirror-back portion until the coatings and silvering are removed from the latter portion of the mirror and the glass surface exposed to the sand blast is ground somewhat whereby the figure 7 may be readily fixed thereto, it being particularly noted that the line of the edge of the silvering provided by the use of the template is particularly sharp and distinct.

It will now be noted that if a picture be placed behind a ground glass surface, a cer-

tain amount of the detail thereof is lost, even though such surface be first treated with turpentine or other agent for increasing the transparency of a ground glass surface.

5 Accordingly, the template is preferably arranged so that only the extreme boundary of the picture-receiving area is subjected to the action of the sand blast, after which the silvering and other coatings within the 10 area are removed by some other method such as by scraping or the use of an etching acid whereby the major portion of the glass surface covered by the picture has an unground surface. As here shown, the template is 15 formed with an auxiliary section 18, such section being of the same outline as the opening 16 of the template and slightly smaller than such opening whereby it may be disposed and held as by a press screw 19 20 carried by and between a pair of the clamps 17 in said opening to define with the opposed edge thereof a relatively narrow space 21 defining the outline of the picture 7, preferably the space 21 is about one-eighth of 25 an inch wide. The strip of ground glass surface produced by the sand-blasting is treated, as with turpentine, to make it as transparent as possible before applying the picture to the space provided therefor.

30 After the picture is applied, coatings 22 and 23 corresponding respectively to the coatings 11 and 12 covering the silvering are preferably applied to the back thereof to protect the picture from air and moisture.

35 It will now be noted that the template provided, being formed of material which resists the action of the sand blast, may be used repeatedly, whereby an absolute constancy of results may be obtained in mount-

ing pictures of a given outline on different 40 mirrors. In this manner, the quantity production of decorated mirrors is facilitated and cheapened.

If desired, and as indicated in Figure 4, the use of the auxiliary template section 18 45 may be dispensed with whereby the entire area 24 of the glass 26 which is to receive the picture is ground, with the result that the picture is "softened" in appearance, as viewed from the front of the mirror, such 50 effect being preferable in some instances.

I claim:

1. In apparatus for removing a predetermined area of the silvering from a mirror back, a pair of form retaining templates 55 cooperative to define the shape of the outline of said area and parallelly spaced, and means for clamping said templates against said mirror back whereby the area defined between the parallelly spaced templates may have its silvering removed by sand-blasting to define the outline of said area to be removed.

2. In apparatus for removing a predetermined area of a coating from the back of a transparent plate, form-retaining templates cooperative to define the shape of the outline of said area and generally parallelly spaced, and means for non-adherently securing said templates against said plate 65 back whereby the area defined between the parallelly spaced templates may have its coating removed to define the outline of the entire area to be removed, and the templates may be removed for repeated use.

In testimony whereof, I affix my signature.

CHARLES R. LAUGEL.
